UNITED STATES PATENT OFFICE.

LUCIAN E. PARKER, OF WADSWORTH, OHIO, ASSIGNOR TO EDWIN J. YOUNG, OF WADSWORTH, OHIO.

WIRE-LOOP-TWISTING MACHINE.

1,385,582.

Specification of Letters Patent. Patented July 26, 1921.

Application filed April 21, 1919. Serial No. 291,566.

To all whom it may concern:

Be it known that I, LUCIAN E. PARKER, a citizen of the United States, residing at Wadsworth, in the county of Medina and 5 State of Ohio, have invented a certain new and useful Improvement in Wire-Loop-Twisting Machines, of which the following is a full, clear, and exact description.

The object of this invention is to provide 10 a machine for forming loops or eyes in the ends of wire to adapt such wires for use as ties or fasteners for bales, boxes, packages, and containers, and for other purposes.

The invention consists of a machine of the 15 character just mentioned, having a rotary reciprocating looper, coöperating with a rotary reciprocating twister about which the looper bends the wire into loop form, so that the twister upon being given its motion will 20 twist the looped end of the wire and thereby form a permanently closed loop or eye in the wire and then discharge same, as I will proceed now to explain and finally claim.

In the accompanying drawings illustrating 25 the invention, in the several figures of which like parts are similarly designated, Figure 1 is a side elevation; Fig. 2 is an end elevation, and Fig. 3 is a top plan view showing one embodiment of my invention, the 30 parts being shown in the position they will occupy when the loop is fully twisted and the machine is about to reverse. Fig. 4 is a vertical section taken substantially in the plane of line 4—4 of Fig. 1. Fig. 5 is a top plan view, Fig. 6 is a side elevation, and 35 Fig. 7 is an end elevation of the twister. Fig. 8 is an elevation and Fig. 9 is an inverted plan view of the looper. Fig. 10 is a perspective view, on a larger scale, illustrating 40 the conjunction of the looper, twister, and wire guide. Fig. 11 is a top plan view, in diagrammatic form, of portions of the looper and twister, indicating the mode of 45 operation. Fig. 12 is a plan view of the product of the machine.

The machine as illustrated in the drawings, comprises a bottom bracket or frame 1 on which is mounted a stud shaft 2, provided with a gear wheel 3. The upper part of the 50 bracket or frame 1 has an opening 4 and a table 5 on one side thereof and a half-bearing 6 on the other side thereof, this half-bearing receiving the spindle 7 of the loop twister, the rear end of said twister spindle 55 having a pinion 8 meshing with the gear

wheel 3 and deriving rotary motion from said gear wheel.

An upper bracket or frame 9 has the other half 10 of a bearing to coöperate with the half-bearing 6 to form a complete bearing 60 for the spindle 7, the said upper bracket or frame being bolted to the lower bracket or frame by bolts 11 or otherwise secured detachably thereto.

The upper bracket or frame 9 is provided 65 with a vertically disposed bearing 12 in which is placed the spindle 13 of the looper 14, and this spindle has at its upper end a pinion 15 by which it and the looper may be rotated. The looper is provided with a 70 roller 16 terminating preferably in a reduced roughened, knurled, or other suitably formed nipping or clamping surface 17. This roller may be mounted to turn upon a spindle 18 held in the socket piece 19 of 75 the looper, as by means of the set-screw 20. The roller 16 is arranged eccentrically with relation to the spindle 13, so that upon rotation of the spindle the roller will move in a circular path about the twister pin 21 which 80 is mounted upon and moves with the spindle 7, said twister pin 21 being located within the space 4 between the brackets or frames 1 and 9 and out of line with the loop-forming 85 roller.

Taking the spindle 7 of the twister as the axis of the twister, and the spindle 13 as the axis of the looper, it will be seen that the looper and twister are arranged in planes substantially at right angles to one another, 90 and this results in the proper formation of the loop.

On the table 5 is arranged a combined 95 wire guide and grip, same comprising a plate 22 having an undercut lip 23, this plate being held in position by screws 24 and suitably adjusted by means of screws 25. The undercut lip forms a hold-down passage for the wire to be looped, and is so arranged relatively to the twister pin 21 that the wire 100 will pass to one side of said pin and be arrested by means of a vertically disposed stop or abutment 26 on the spindle 7.

Two cams are used to give motion to the 105 parts, and these cams are designated 27 and 28, respectively, same being mounted on a drive shaft 29 which has bearings in the upper part of the upper bracket or frame 9. The cam 27 is provided with a cam groove 30 which is engaged by a roller 31 on a hori-

zontally reciprocating toothed rack 32 suitably supported in the bracket or frame and engaging the pinion 15 of the looper and having a forked end 33 which straddles the 5 shaft 29 for support. Obviously, as the cam revolves, the cam groove 30 will so act upon the roller 31 as to cause the toothed rack 32 to reciprocate and accordingly impart to the spindle 13 a rotary reciprocating motion.

10 The gear wheel 3 and consequently the spindle 7 will be given a rotary reciprocating motion by means of a toothed rack 34 which has a roller 35 which travels in a cam path 36 in the cam 28, and this toothed rack 34 15 likewise has a forked end 37 which straddles the shaft 29. The toothed rack 34 engages a pinion 38 on the stud shaft 2 and is adapted to turn said shaft and thereby turn the gear wheel 3 which transmits its motion to 20 the twister as already described. The toothed rack 34 may be arranged in suitable guides on the brackets or frames.

As indicated in Fig. 11, the wire to be provided with the loop or eye is fed into the 25 machine under the lip 23, past the twister pin 21 until it comes up against the abutment 26. Rotary motion being imparted to the machine, the looper engages the inserted end of the wire and loops it around the 30 twister pin and clamps it between its roller 16 and the guide 22, while the twister spindle is turned axially and the twister pin with the looped wire held thereby is turned over so as to twist the looped end of the wire 35 around the adjacent body of the wire as shown, and then upon a reverse movement of these parts, the twister pin is righted and the loop slips off of it. In order to facilitate the discharge of the formed loop the 40 twister pin is made with a slabbed off portion 39.

As shown in Fig. 11, the position A of the looper represents the looper as it stands when it has rotated to a position to engage 45 the free end of the wire, and it then moves over into the position B so as in its travel through an arc of a circle to loop such wire end about the twister pin and then clamp the wire between itself and the guide. When the 50 wire is clamped as last explained, the twister spindle is axially rotated in the direction of the arrow to twist the looped end about the body of the wire to close the loop, and when that is accomplished the twister pin 55 is again brought into upright position, discharging the looped end and assuming a position to receive another loop upon repetition of the initial movements, and twist it.

60 Variations in details of construction and arrangement of parts are intended and deemed to be within the spirit and scope of the invention as claimed.

What I claim is:—

1. A machine for forming loops in wires,

having a rotary reciprocating looper, a wire 65 guide, and a rotary reciprocating twister, said looper and twister being arranged in planes substantially at right angles to one another, said twister being provided with a pin about which the looper bends the wire 70 and thereafter clamps such bent portion between itself and the guide while the twister is turning to twist the bent portion upon the body of the wire.

2. A machine for forming loops in wires, 75 having a rotary reciprocating looper, composed of a vertically disposed spindle provided at one end with an eccentrically arranged wire-bending device, a stationary wire guide, and a rotary reciprocating 80 twister comprising a spindle arranged horizontally beneath the looper and having a twister pin arranged perpendicular to said spindle about which the looper travels in an arc of a circle to bend the wire about it 85 and thereafter clamp it against the guide while being twisted.

3. A machine for forming loops in wires, 90 having a rotary reciprocating looper, a stationary wire guide having an undercut lip 95 to receive a wire to be looped, and a rotary reciprocating twister, the looper and the twister being arranged in planes substantially at right angles to one another, and the twister being provided with a pin about which the looper bends the wire and thereafter clamps such bent portions between itself and the guide while the twister is turning to twist the bent portion upon the body of the wire.

100 4. A machine for forming loops in wires, having a vertically disposed looper spindle provided with an eccentrically arranged looper roller terminating in a clamping member, means to impart a rotary reciprocating motion to the looper spindle, a stationary wire guide with which the roller co-operates to clamp the looped end of a wire, a horizontally arranged twister spindle located below the looper and provided with a twister pin about which pin the end of the 105 wire is looped by the action of the looper, and means to impart a rotary reciprocating motion to the twister spindle.

115 5. A machine for forming loops in wires, having a vertically disposed looper spindle provided with an eccentrically arranged looper roller terminating in a clamping member, means to impart a rotary reciprocating motion to the looper spindle, a stationary wire guide with which the roller co-operates to clamp the looped end of a wire, a horizontally arranged twister spindle located below the looper and provided with a twister pin about which the end of the 120 wire is looped by the action of the looper and having an abutment by which the inserted end of a wire to be looped is arrested pre-

liminarily to the formation of the loop, and means to impart a rotary reciprocating motion to the twister spindle.

6. In a wire loop twisting machine, having a vertically arranged looper provided with a pinion, a rack engaging said pinion, a cam for imparting reciprocating motion to said rack, a stationary wire guide, a twister arranged beneath the looper on a horizontal axis and provided with a pinion,

a toothed rack, a cam for imparting reciprocating motion to said rack, and gearing interposed between said rack and twister pinion.

In testimony whereof I have hereunto set 15 my hand this 19th day of April A. D. 1919.

LUCIAN E. PARKER.
